CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY

HEAT EXCHANGER

Application filed November 22, 1928. Serial No. 321,151.

This invention relates to heat exchange apparatus, and more particularly to devices adapted to be used in conjunction with compressors for cooling the air between stages of compression or between the final stage of compression and the storage receiver.

One object of the invention is to obtain a compact and efficient cooling unit in which liquid conveying tubes may be arranged in close proximity to the walls of the heat exchanger.

Another object is to avoid the formation of what may be termed dead air pockets in the heat exchanger by means adapted to insure a state of turbulence in the heat exchanger so that the fluid intended to be cooled will be brought into repeated and intimate contact with the surface of the cooling tubes.

20 Other objects will be in part obvious and in part pointed out hereinafter.

In the drawings illustrating a practical application of the invention and in which similar reference characters refer to similar parts,

Figure 1 is a longitudinal vertical section of a heat exchanger constructed in accordance with the practice of the invention,

Figure 2 is a transverse view taken 30 through Figure 1 on the line 2-2 looking in the direction indicated by the arrows,

Figure 3 is an enlarged detail sectional elevation of one end of a heat exchanger, and

35 Figure 4 is a transverse view taken through Figure 1 on the line 4-4 looking in the direction indicated by the arrows.

Referring more particularly to the drawings, A designates generally a heat exchanger having a casing B in which is disposed a group of cooling liquid conveying tubes C. The casing B comprises in this instance a tubular section D to one end of which is secured a head E and at the other end an extension F of substantially the same diameter as the tubular section D to accommodate a group of cooling tubes C. A closure is provided for the outer end of the extension F in the form of a cover or head G which may be secured to the extension F in

any suitable manner, as for instance by bolts H.

For convenience of illustration, only a single pass cooler is illustrated. It will, however, be apparent to those skilled in the art from the following description that the invention is also applicable to multi-pass coolers or heat exchangers.

According to the construction shown, the element intended to be cooled, such as pressure fluid issuing from a compressor, enters the casing B through an inlet opening J formed in this instance in the extension F. The pressure fluid therefore enters one end of the heat exchanger and is caused to flow 65 through the casing B along a serpentine path formed by baffles K which are in this instance disposed in staggered relationship with respect to each other throughout the casing to cause the fluid to be brought well 70 into contact with the surfaces of the cooling tubes C.

Any suitable number of baffles may be provided for the purpose described and these baffles are so spaced with respect to each other and the sides or ends L of the baffles K over which the pressure fluid flows are preferably so spaced with respect to the bounding surface of the casing that substantially the same pressure may exist throughout the entire area of the heat exchanger. In other words, the space between the ends L of the baffles K and the wall of the casing is preferably such that there is neither a substantial decrease nor increase in the pressure 85 of the fluid during its course through the exchanger A.

After passing over the baffle K adjacent the head E of the heat exchanger, the pressure fluid will flow against a grid or separator O forming in this instance an integral portion of the head E. The separator O may be in the form of a series of ribs P which, when the pressure fluid contacts therewith, will have the effect of extracting moisture from the pressure fluid immediately before the exit of such pressure fluid through an outlet opening Q of the head E.

The ribs P may be arranged in any suitable manner in opposite sides of the head E

and between the opposed series of ribs P and on the bottom of the head E is a bridge R also integral with the head E and having teeth or ribs S and T declining in opposite directions for extracting moisture and the like from the pressure fluid and for draining such moisture to the bottom of the head E from whence it may be conveniently conveyed by means of a drain pipe U.

10 Owing to the wide variation of temperatures to which devices of this type are subjected, it is essential that means be provided to accommodate the free elongation and contractional movement of the tubes C. To this

15 end the tubes are seated with one end in a tube plate V fixedly secured to the head E and at the other ends are inserted in what may be termed a movable tube plate W. The tube plate W lies within the confines

20 of the casing and is preferably of sufficiently smaller diameter to enable it to move freely longitudinally of the casing in accordance with the degree of contraction and expansion of the tubes which it supports.

25 Secured to the tube plate V is a head X for cooling liquid, such as water, and into which the water may be conveyed through a pipe Y leading from a suitable source of supply. The water is preferably introduced

30 into the head X at a point near the uppermost portion of the said head X and may flow through a series of tubes C lying in the upper region of the heat exchanger and thence into a head Z bolted to the tube plate

35 W or otherwise suitably secured thereto and forming a chamber b through which water may flow into lower rows of tubes and again be returned to the head X. The chamber b in the head Z and a chamber c in the head X 40 may be suitably divided into any desired number of compartments wherewith adjacent rows of tubes C may communicate so that the direction of the flow of water may be repeatedly reversed until finally it reaches 45 the lowermost portion of the head X from whence it may be conveyed by means of a pipe d.

In apparatus of this character it is desirable that substantially all the available 50 space in the casing B be occupied by the cooling means, such as the tubes C in order to avoid the formation of dead air pockets in which pressure fluid of any temperature may remain substantially motionless and 55 thus act as an insulator to preclude any additional cooling effect which might otherwise take place due to the temperature of the atmosphere surrounding the heat exchanger. The present invention contemplates the elimination of such dead air 60 pockets and to this end the head Z is provided at its edge with an annular flange e of only small width in order that the chamber b for which the flange e forms a bounding 65 surface may be in diameter only slightly

smaller than the diameter of the casing B. The flange e in this instance is adapted to encircle a boss f of the tube plate W and a gasket g is disposed between the flange e and the tube plate W to seal the chamber b. 70 By forming the flange e in the manner described the means whereby the head Z is secured to the tube plate W, such as the bolts h, are inserted through the head Z at points within the inner surface of the 75 flange e. This arrangement will permit of the disposal of cooling tubes C at points close to the casing and therefore throughout substantially the entire area of the casing.

Formerly, in heat exchanging apparatus 80 it has been customary to depend entirely upon the natural flow of the pressure fluid through the heat exchanger to cause agitation of the pressure fluid so that it may be uniformly distributed throughout the heat 85 exchanger and brought into contact with the entire available cooling surfaces of the tubes C. While this was the desired result, it was found that in practice the main fluid stream followed the serpentine course here- 90 inbefore referred to and that there were considerable areas in the casing in which pressure fluid remained comparatively dormant, thus insulating not only the casing of the heat exchanger but also considerable 95 areas of the cooling tubes C. In order therefore to insure a desirable state of turbulence throughout the entire area of the casing, the baffles K are pro- 100 vided with passages j for diverting a 100 portion of the pressure fluid from the main fluid stream. The pressure fluid enters the passages j from the up-stream side of the baffles and injects such pressure fluid laterally into the main fluid stream to insure 105 its thorough agitation so that the pressure fluid comprising the main fluid stream will not only flow along its general course to- 110 wards the outlet opening Q but will be diffused and will therefore be brought into 110 repeated contact with the surfaces of the cooling tubes C. The passages j may be of 115 any suitable number and conformation and are preferably located on diametrically op- 115 posite sides of the tubes C, and for conven- 120 ience of manufacturing, they also prefer- 120 ably open into apertures k in the baffles K through which the tubes C extend. The apertures k are of such diameter that the walls thereof may be in body contact with 120 the tubes so that the tubes may be suitably supported at points intermediate their ends.

The operation of the device is as follows: Assuming the machine, such as a compres- 125 sor, to which the heat exchanger may be attached to be in operation, compressed fluid entering the inlet opening J will flow over the ends L of the baffles K through the cas- 130 ing B and into the head E where, upon striking the ribs, P, S and T of the sepa-

5 rator, any moisture or other matter entrained by the fluid will be separated from the fluid. This scouring process preferably takes place just before the fluid leaves the casing through the outlet opening Q from whence it may flow to a storage receiver, where only one unit is being utilized or, in case of a two pass exchanger, into the connected unit.

10 10 During the course of the fluid through the casing B, fluid will enter the passages on the up-stream side of the baffles K and will flow through the passages to be again injected in a longitudinal direction relatively to the casing into the main fluid stream. In this way the fluid will be thoroughly agitated to prevent the undesirable insulating effect hereinbefore referred to.

I claim:

20 1. A heat exchanger, comprising a casing, tubes in the casing for conveying cooling liquid, baffles in the casing arranged in staggered relation with respect to each other to direct fluid flowing through the casing into intimate contact with the tubes, and a separator integral with the casing for removing moisture entrained by the fluid intended to be cooled.

25 2. A heat exchanger, comprising a casing having an inlet and an outlet opening, tubes in the casing for conveying cooling liquid through the casing, baffles in the casing, passages in the baffles to direct a portion of the fluid intended to be cooled longitudinally of the casing and in the direction of the outlet opening to agitate the main fluid stream and insure its intimate and repeated contact with the tubes, and a separator integral with the casing and in the same transverse plane as the outlet opening for removing moisture entrained by the fluid intended to be cooled.

30 3. A heat exchanger, comprising a casing, tubes in the casing for conveying cooling liquid, a tube plate affixed to the casing for supporting the tubes at one end, a movable tube plate in the casing to support the opposite ends of the tubes and having a boss, a head for the movable tube plate, a flange on the head to form a chamber for cooling liquid and encircling the boss to seal the chamber, and means lying within the inner surface of the flange for securing the head to the movable tube sheet.

35 4. A heat exchanger, comprising a casing, tubes in the casing for conveying cooling liquid, a tube plate affixed to the casing for supporting the tubes at one end, a movable tube plate in the casing to support the opposite ends of the tubes, a head for the movable tube plate having an annular flange to form a chamber for cooling liquid, and bolts lying within the inner surface of the flange for securing the head to the movable tube plate.

5. A heat exchanger, comprising a casing, baffles in the casing having apertures therein, liquid conveying tubes extending through the apertures, said tubes being supported against lateral movement by the baffles, and separate passages in the baffles for each tube to divert a portion of the fluid flowing through the casing and inject it laterally into the main stream for agitating the fluid and thus insure its intimate contact with the tubes.

70 6. A heat exchanger, comprising a casing, baffles in the casing having apertures therein, liquid conveying tubes extending through the apertures, said tubes being supported against lateral movement intermediate their ends by the baffles, and separate passages for each tube in the baffles adjacent the apertures and coalescing therewith to divert a portion of the fluid flowing through the casing and inject it laterally into the main stream for agitating the fluid and thus insure its intimate contact with the tubes.

75 80 In testimony whereof I have signed this specification.
